WINDOW AND VENETIAN BLIND COMBINATION

Theodore Hauck, Amityville, N.Y., assignor to General Bronze Corporation, Garden City, N.Y.
Filed Mar. 17, 1965, Ser. No. 440,533
3 Claims. (Cl. 160—107)

This invention relates to a window combination including a frame, sash and Venetian blind.

An object of the invention is to provide a window structure in which the Venetian blind operating mechanism may be freely placed in and removed from a pocket at the upper end of the sash and in such position that it will substantially be covered by the upper horizontal stile of the sash.

An object of the invention is to provide a unitary Venetian blind structure in which the tilting of the slats and the raising or lowering of the blind may be accomplished by a continuous movement of a crank operating handle.

Another object of the invention resides in so constructing the mechanism that the window frame and sash may be of simple construction.

It is a further object of the invention to permanently house the operating mechanism for the tilting of the slats and for the raising and lowering of the blind in a casing which may be emplaced and removed from the sash as a unit.

A still further object of the invention lies in the provision of such a structure as above set forth which is adapted for use with windows of various types including those having single glazed frames, those having double glazed frames in which both frames are stationary, or in which one frame is hinged to the other, and permanently emplaced frames or sash frames of the pivoted type.

In the drawing, I have chosen to illustrate the invention as incorporated in a window which comprises a frame, a pivoted primary sash and a secondary sash hinged to the pivoted sash but, as I have pointed out, the invention is not limited to such a use or construction,

Referring now to the drawings,

FIGURE 1 is a perspective view of the pivoted-hinged type of window, showing both sash frames in open position;

FIGURE 2 is a face view, looking from the inside of the window with both sashes closed;

FIGURE 3 is a vertical sectional view in the plane of line 3—3 of FIGURE 2;

FIGURE 4 is a vertical sectional view in the plane of line 4—4 of FIGURE 3;

FIGURE 5 is a horizontal sectional view in the plane of line 5—5 of FIGURE 4;

FIGURE 6 is a perspective view, partly in section, of the slat titling and blind raising and lowering mechanism;

FIGURE 7 is a perspective view, partly in section, of the slat titling drum and its associated parts; and

FIGURE 8 is a longitudinal sectional view of the clutch mechanism and its associated parts.

The window illustrated comprises a frame 1 of rectangular form. A primary sash frame 2 is pivoted on vertical pivots 3 to swing to open and closed positions, it being shown in FIGURE 1 in a partly open position. A secondary sash frame 4 is hinged at 5 to the primary sash frame 2 in such manner that it may be closed against or swung open from the primary frame when the latter is either in the opened or closed positions.

The secondary sash frame is provided with a continuous inwardly extending flange 6 which protrudes from the vertical and horizontal stiles 7, 8, 9 and 10. The Venetian blind and its operating mechanism are located within the confines of the flange. The Venetian

2

blind is of the ordinary slat type, having slats 11 which are provided with the usual rasing and lowering cords 12 and with the tilting cords, 13, 14, 15 and 16, which may be of any desirable flexible material.

5 The housing 17 for the operating mechanism is adapted to fit within a pocket 18 in the upper stile of the hinged sash and is of such small vertical and horizontal dimensions that it is substantially covered from the outside of the window by the stile 8 and is only slightly less in length than the horizontal measurement of the upper horizontal portion of the flange 6.

The housing 17 is maintained, removably, in the pocket 18 by a spring-biased shaft 19, one end 20 of which is rotatably mounted in a bearing 21 carried by the housing. 15 The other end of the shaft is rotatably and removably mounted in a bearing 22 in the upper vertical portion of the flange 6 of the hinged frame.

The shaft is normally positioned with its end in the bearings, as described, by a gear 23, a spring 24 and a 20 stop 25 secured to the shaft 19, the spring normally urging, through the stop 25, the end 20 of the shaft into its bearing 21 and at the same time urging gear 23 into engagement with an actuating gear 23' later to be described.

25 All of the tilting and raising and lowering mechanism is mounted on the shaft 19.

The housing 17 may be locked in the pocket 18 by spring clips 18' which releasably engage with the edges of the open side of the pocket 18 at 18'' to prevent accidental displacement.

30 To simultaneously remove the housing with the raising and lowering and tilting mechanism and the Venetian blind as a unit, it is only necessary to move the housing longitudinally at which time the end of the housing carrying the bearing 21 may first be withdrawn from the pocket 18 in which the housing is mounted. This will then permit the disengagement of the gears 23 and 23' and the removal of the adjacent end of the shaft from the bearing 22.

35 Beyond the operating mechanism which is carried by the housing 17, the entire mechanism includes only a simple actuating mechanism which is located on the inner side of a vertical flange 6. This mechanism comprises a vertical shaft 27 which fixedly carries the gear 23' referred to above. This shaft 27 is mounted in a series of bearings 28 protruding from the flange 6. The lower end of the shaft 27 fixedly carries a gear 29 which intermeshes with a gear 30, having a hub 31 which rotates in a bearing 32. The gear 30 is maintained in its position with the hub 31 within the bearing 32 by a spacer 33 which is inserted in the casing 34 through an opening therein. The spacer is provided with a head 35 which abuts the casing 34 and is locked in position by a resilient snap-on device, such as a snap-ring 36.

40 In order that the gear 30 may be actuated, I have provided a removable actuating handle 38. A portion of the shank of this crank and the complementary recess in the gear 30 are non-circular in cross-section so that when the crank is rotated it will impart a rotative movement to the gear.

To facilitate the assembly of the shank of the crank into the gear, I have made the leading portion 40 thereof substantially circular in cross-section, so that it may enter the recess in the gear 30 irrespective of the position of the rectangular opening therein.

45 In order that the Venetian blind may be raised and lowered after the slats have been tilted to their proper positions, I have provided the following:

The shaft 19 is provided with two spools 41 and 42 which are secured to the shaft and rotate with it. The raising and lowering cords 12 are wound onto and unwound

rom these spools upon the rotation of the shaft 19 by the
ctuating mechanism.

In order that the slats may be tilted to the proper positions irrespective of whether or not the blind is raised, lowered, or partially raised, or partially lowered, I have provided the following mechanism:

The shaft 19 which is continuous from end-to-end carries a cylindrical drum 43 which, when actuated, tilts the slats into its various tiltable positions.

The housing 17 is provided with a pulley 44 at one end and a similar pulley 45 at the opposite end, around which pulleys, a continuous band 46 is arranged. This band lies within the housing 17 and, as it is moved back and forth tilts the slats. This movement of the band 46 will move the connections 49 and 50 between the cords 47 and 48 and the cords 13, 14, 15 and 16 in opposite directions, depending upon the direction of rotation of the drum 43. This will result in the application of a tilting pull to either the pair of cords 13 and 15 or the pair 14 and 16, depending upon the direction of movement of the drum.

In order that the slats may be tilted to any of their possible angular positions by this application of force through the action of the cords 47 and 48, before, after, or during the raising or lowering of the blind, I have provided the following mechanism:

The shaft 19 whose end 20 is supported in the bearing 21 at one end of the housing, extends through and is supported by a second bearing 54. A pair of spaced brackets 55 and 56 are secured to the base of the casing, the shaft 19 passing through an opening in the bracket 55 and through a notch 57 in the bracket 56, which notch provides a pair of shoulders 58 and 59. The drum 43 which has heretofore been referred to is fixedly mounted on the shaft 19. Within the drum 43 and spaced from the drum base 60 is a metallic clutch plate 61 having a sleeve 61' extending freely through said base. This plate is movable on the shaft in longitudinal directions and is rotatable with the shaft.

Between the base 60 of the drum 43 and the clutch plate 61 is located a cork clutch facing 62. Washers 63 and 64 of material having low coefficient of friction, such as Teflon, are located on opposite sides of the metallic bracket 55.

The sleeve 61' carries two spaced metallic washers 65 and 66 between which is a sleeve embracing spring 67. Locking means for this assembly is mounted on the shaft 19 and in the form shown comprises adjusting screw-threads and lock nuts 68 adjustably mounted upon the shaft 19 and provided with means for securing the lock nuts to the sleeve. The purpose of this spring is to cause the frictional engagement between the faces of the clutch plate 61, the cork member 62, and the base 60 of the drum 43, and the purpose of the spring 67 is to vary the force with which these clutch faces engage so that the tilting mechanism may be adjusted to operate with blinds of various weights.

One of the cords 47 or 48 passes from the point of attachment 49 or 50 to the band 46 around a roller 53 and thence around the drum 43 to a point of attachment 69, in a clockwise or counterclockwise direction, while the other of these cords passes under the roller 53 and around the drum 43 in the opposite direction and is attached at 70 to the drum at a point diametrically opposite the point of attachment 69. Thus upon the rotation of this drum in one or the other of its directions of rotation, one of the cords 47 or 48 will rotate the drum while the other is released to permit such rotation. Since the cords 47 and 48 are connected to the tilting cords 13, 14, 15 and 16 the partial rotation of the drum 43 will tilt the slats into their possible positions of tilting.

However, the drum 43 is provided with a stop member 71 which is engageable with the shoulders 58 or 59 according to the direction of rotation of the drum. The engagement of this stop member 71 with one of the

shoulders will arrest the movement of the drum, this arresting of the movement being permitted by the slipping of the clutch plates. Thus the continued rotation of the shaft 19 caused by the handle 38 will have no effect upon the tilting of the slats but will raise or lower the blind.

When the handle 38 is first actuated, the gear 66 and its associated gear train will through the gear 23 rotate the shaft 19. This rotation of the shaft will wind the cords 12 upon the spools 41 and 42 and will rotate the drum 43 in one direction. This rotation of the drum will, through the gears 47 or 48, move the band 46 around the pulleys and, because of the attachment of the cords 13 and 14 and 15 and 16 to this band 46 of the points 49 and 50, the slats will be tilted. This tilting will continue until the stop 71 moves from one shoulder 58 or 59 to the opposite shoulder at which time the rotation of the drum will be arrested because of the slippage of the clutch. However, the rotation of the shaft and of the spools 41 and 42 will continue.

Thus, the initial movement of the operating handle will tilt the slats and the continued and uninterrupted movement of the handle will raise or lower the blind to the desired degree.

This tilting of the slats may be accomplished regardless of whether or not the blind is in a raised, lowered or intermediate position. When it is desired to remove the casing and the raising and lowering mechanism, and the Venetian blind as a unit, it is only necessary to move the casing longitudinally (as for instance to the right in FIGURE 6) in the pocket to a slight degree. This will permit the disengagement of the opposite end of the shaft from the bearing opening 22 and will permit the disengagement of the gear 23 from the gear 26. The assembly may then be removed as a unit by first withdrawing the end of the casing at the bearing end 20 from the pocket and then the opposite end of the casing. If the locking clips 13' are used these, of course, will be first removed.

Thus it will be seen that I have provided a Venetian blind combination including a blind, a housing for the tilting and raising and lowering mechanism for the blind which may be inserted in and removed as a unit from an open pocket which housing is substantially coextensive with and hidden by the upper stile of the window sash. I have also provided such a mechanism in combination with two window sashes, one of which is hinged to the other, and each of which is provided with a glass so that when the sashes are closed, one against the other, the Venetian blind and its operating mechanism will be located between and protected by the glass of the sashes.

In this specification I have spoken of cords but I wish it to be understood that by cords I means to include tapes and other elongated flexible members which will perform the functions of the cords in this invention.

While I have illustrated and described a particular embodiment of the invention, it will be understood that many modifications may be made and will occur to those skilled in the art. I, therefore, do not wish to be limited to this particular disclosure except as is made necessary by the claims.

What I claim is:

1. In combination, a window sash comprising upper and side stiles, a pocket member adjacent to said upper stile, a housing removably mounted in said pocket member, a Venetian blind raising, lowering and slat-tilting mechanism permanently mounted in said housing, a Venetian blind suspended from said mechanism, and actuating means connected to and actuated by said mechanism to transmit motion from said mechanism to said blind to tilt the slats thereof and to raise and lower said blind, said housing, mechanism and blind being removable from said sash as a unit, said Venetian blind raising, lowering and slat-tilting mechanism comprising a shaft rotatably mounted in said housing, a pair of winding spools rotatable with said shaft, and a clutch-con-

trolled drum rotatable on said shaft, said slat-tilting actuating means comprising cords attached to said slats and windable on said drum, and cords being attached to said spools and to said slats for lowering and raising the blind, and means for resiliently urging said housing against one end of said pocket member to maintain said housing in position in said pocket member, said sash being mounted in a stationary window frame, and said frame being provided with an actuating gear for said shaft and a gear slidably mounted on said shaft and spring-pressed into engagement with said first mentioned gear.

2. In combination, a window sash comprising upper and side stiles, a pocket member adjacent to said upper stile, a housing removably mounted in said pocket member, a Venetian blind raising, lowering and slat-tilting mechanisms permanently mounted in said housing, a Venetian blind suspended from said mechanism, and actuating means connected to and actuated by said mechanism to transmit motion from said mechanism to said blind to tilt the slats thereof and to raise and lower said blind, said housing, mechanism and blind being removable from said sash as a unit, said Venetian blind raising, lowering and slat-tilting mechanism comprising a shaft rotatably mounted in said housing, a clutch-controlled drum rotatable on said shaft, cords attached to said slats and windable on said shaft, cords attached to said drum to said

slats for tilting the blind, said sash being mounted in a window frame, a gear mounted on said shaft, a gear carried by said window frame engageable with and disengageable from said first mentioned gear mounted on said window frame, and means for actuating said gears.

5 3. The combination recited in claim 2 wherein said gears are spring-pressed into engagement with each other.
